UNITED STATES PATENT OFFICE

2,430,380

SHIP HULL

David H. Welsh, Sr., Duluth, Minn.

Application November 8, 1943, Serial No. 509,507

4 Claims. (Cl. 114—57)

1

This invention relates particularly to a ship's hull and to that class of ship which may aptly be referred to as a relatively high speed, light draft cargo and/or passenger ship.

The principal object of the improved shape of hull and impeller installation is to lessen as much as possible the skin friction of the hull when being propelled through the water.

Another object is to so shape the hull that the minimum of labor and skill in shaping and fitting the material in the construction of same is required.

Still another important object is to provide such a hull having a normal tendency to lessen the draft in the fore part of the ship as the forward speed thereof increases simultaneously with confining and directing the least disturbed water directly to the impellers of the ship at the stern thereof.

A further important object is to provide a shape of hull that will have the minimum of tendency to displace water laterally therefrom when being navigated forwardly therethrough, but rather to keep it as firm and level as possible and within predetermined defined channels under the after portion of the hull when being so navigated.

Other objects and advantages will appear in the further description of the invention.

Referring now to the accompanying drawings forming part of this application and in which like reference characters indicate like parts:

Figure 1 is a side elevation of the hull of a ship embodying my invention, having the after portion of the near skeg broken away.

Figure 2 is a main deck plan view showing the relative position of the trunk deck.

Figure 3 is the outline of an enlarged transverse sectional view on the line 3—3 Figure 1, and

Figure 4 is a similarly enlarged combined bow elevation on one side thereof and the other side an outlined transverse section on the line 4—4 Figure 2.

The entire hull is substantially rectangular in cross section, though with somewhat varied forms of flat surfaces or facets with a view of using as large a proportion as possible of mill run construction plates and with as little shaping as possible.

As is well known for ideal results in boat navigation, especially in the smaller type of ship construction, the major cross-sectional area of the vessel is at a point approximately one-third of the length thereof from the bow and which I have learned by actual experiments with a large self-propelled model to be the ideal point from which

2

to taper the hull both fore and aft for best results during high speed navigation of the instant novel shape of hull.

At this critical point indicated by the line 1—1, the hull is rectangular in cross-section except that the main deck 1 is stepped downwardly adjacent the two opposite sides of the hull forming the foremost tapered end 15 of the trunk 16, the deck 2 of which covers the entire trunk, and 3 represents the relatively small poop deck.

Upon opposite sides of this tapered portion of the trunk, the main deck is gradually inclined upwardly till merging with the flat portion 4 of same over the forward approximately one-half of the forward portion of the hull where both main and trunk decks merge, and it is to be noted that this stepping of the main deck not only provides a relatively short inclined runway 17 upon each side of the forward end of the trunk, but has the advantage of increasing the headroom therewith and the strengthening of the entire hull structure and also provides the short triangular strip of bulwark 18 for the inclined runways by the extension of an integral part of the sides 20 of the hull.

Forwardly of this trunk construction the hull is reinforced in a somewhat similar manner by the depending forefoot portion 5 for initial engagement with the water as the ship is navigated therethrough and while this forefoot portion seems to take on a somewhat skeg-like shape, there is no thwartship line through the outer surface thereof which is concave in any sense, thus conserving throughout the advantages of the 25 resistive properties of a convex surface where the wave abuse is greater.

Then for the double purpose herein after described, there is provided the plurality of thin, fine-like spaced skegs 6—7—8—9 and 10 depending from and forming an integral part of the bottom of the entire after part of the hull to beneath the poop 3, and below which each is equipped with a rudder blade 11 controlled in any suitable manner, not shown, from the interior of the ship.

Within each channel-like conduit thus formed intermediate of each pair of these skegs and just forwardly of a plane with the rudder pivots is installed a propeller wheel 12 driven in any desired manner, also not shown, from the interior of the ship.

It is to be noted that the lower line of these skegs is parallel with the trunk deck and that the bottom 13 of the hull which is perfectly flat, is inclined upwardly from the critical point previously

referred to, aft to some little distance forwardly of the propeller wheels 12 where it inclines upwardly more rapidly as at 14 to provide better accessibility of water to the propellers 12, and to prevent backward suction of the stern of the ship which otherwise would occur.

It is well known that where a rudder is installed rearwardly, through intermediate of two propellers instead of directly behind them, the vibration caused by the propeller and transmitted to the ship is much less; and in this respect the instant arrangement has proven ideal; furthermore the control of the ship, where confined volumes of water are thus fed to each propeller is exceedingly effective at all times and almost wholly regardless of the wave condition of water being navigated.

The strongly skegged fore foot first to engage any wave condition, does so with the least possible retarding of motion to the hull and being instantly followed by the wide inclined flaring flat bottom upon either side of the medial line of the hull and the sharp angle formed by the juncture of the flat sides and convex fore foot surfaces seems to level off and quiet the disturbance of the parting of the water most effectively. This occurs simultaneously with over-balancing the after part of the ship and augmenting its hold in the water where it is so vital for the propellers to accomplish their best results.

In fact such a ship seems to resemble the action of a Caterpillar tractor in not only laying, but forming its own track in the water, besides markedly leveling off the wave effect initially at the bow and materially preventing rolling of the ship, by confining the large volume of water beneath the after major portion thereof and intermediate of the conduit forming skegs.

Having thus described my invention, what I claim and desire to secure by Letters Patent is:

1. In a ship hull substantially rectangularly shaped in cross section throughout the aftermost two-thirds thereof, a plurality of fin-like skegs depending from the bottom of said hull and increasing in depth towards the stern thereof from a point where they merge with a flat bottom portion of said hull, said point being approximately at the greatest transverse area of said hull, said skegs forming intermediate of each pair thereof a channel-like conduit terminating beneath and adjacent the stern of said hull, a propeller within and at the after end of each conduit, a V-shaped forefoot on said hull merging at its after terminus with the flat bottom thereof at a point coincident with the merging of the forward terminus of said skegs and the flat bottom of said hull.

2. In a ship hull of the character described having a bottom including a flat portion inclined upwardly and rearwardly from the greatest trans-

verse area of said hull and forwardly of midship thereof and extending to near the after end, a plurality of fin-like skegs depending from said flat inclined portion and extending from the beginning of the flat portion nearly to the after end of the hull substantially the full length thereof, thus forming intermediate of each pair of said skegs, a long tapered tunnel-like conduit under the inclined bottom of said hull, a propeller mounted within the after terminus of each of said conduits and a V-shaped substantially straight stemmed forward under portion extending aft and merging with said flat portion under said greatest transverse area of said hull.

15 3. A ship hull as set forth in claim 2 further characterized by said bottom being in two distinct planes rearwardly from said greatest transverse area of said hull, the shorter one being directly under the stern of said hull.

20 4. In a form of ship hull having a plurality of propellers beneath the bottom thereof and having the upper portions of its side walls aft of the greatest transverse dimensions thereof flat throughout, a slightly convex forefoot of V-shape 25 with the sides of the V slightly convex commencing at a point approximately one-third of the total length of the hull from the stem thereof and extending forwardly to said stem and a flat upwardly and rearwardly inclined bottom extending 30 from said point to near the extreme stern where it turns more abruptly to said stern and over said propelling means, said bottom having depending therefrom a plurality of spaced depending fin-like skegs extending its entire length forming elongated tapered channels, one for each of 35 said propeller means and each of said skegs terminating in a rudder.
